Primary Examiner — Paula Allen Greene(74) *Attorney, Agent, or Firm* — Albert Peter Durigon(57) **CLAIM**

The ornamental design for a pillow sound system, as shown and described.

DESCRIPTION

FIG. 1 is a perspective view of the top of the pillow sound system of the present invention;

FIG. 2 is a perspective view of the bottom of the pillow sound system of the present invention;

FIG. 3 is a plan view of the top of the pillow sound system of the present invention;

FIG. 4 is a plan view of the bottom of the pillow sound system of the present invention;

FIG. 5 is a plan view of one side of the pillow sound system of the present invention;

FIG. 6 is a plan view of the other side of the pillow sound system of the present invention;

FIG. 7 is a plan view of one end of the pillow sound system of the present invention taken along the lines 7-7 of FIG. 6; and,

FIG. 8 is a plan view of the other end of the pillow sound system of the present invention taken along the lines 8-8 of FIG. 6.

1 Claim, 5 Drawing Sheets(56)
